UNITED STATES PATENT OFFICE.

LEVI J. WING, OF NEW YORK, N. Y.

HEATING-BURNER.

SPECIFICATION forming part of Letters Patent No. 671,574, dated April 19, 1901.

Application filed February 21, 1900. Serial No. 6,014. (No model.)

To all whom it may concern:

Be it known that I, LEVI J. WING, a citizen of the United States, and a resident of New York, in the county of New York and State of New York, have invented certain new and useful Improvements in Heating-Burners, of which the following is a specification.

My invention relates generally to heating-burners for hydrocarbon gases and more particularly to heating-burners to be used in connection with acetylene gas or gases produced from metallic carbids.

In utilizing acetylene-gas for heating purposes where the heating-flame is confined in an inclosed compartment, such as a flat-iron, I have observed that the flame upon being confined in such compartment is immediately extinguished, notwithstanding the fact that a copious supply of air is fed to the burner from the atmosphere and admixed with the gas prior to or at the point of its combustion. Heretofore in order to overcome this difficulty especial attention has been paid to the method of proportioning and admixing the gases with atmospheric air in order to obtain a uniform and perfect combustion. My device, on the other hand, can be fitted to any burner of the Bunsen type and does not depend entirely for its success upon the method in which the gases are admixed, but upon a regulating attachment for regulating the combustion of the particles, so as to render the said combustion more uniform and complete.

Accordingly one object of my invention is to produce a burner in which the combustion of the gases will continue after the flame is confined in an inclosed compartment, such as a flat-iron or the like.

A further object of my invention is to produce a heating-burner in which the combustion of the admixture of gas and air is made perfect and uniform—in other words, a device which will compensate for the non-uniformity of the flow of the heating fluid through same by consuming all non-oxidized particles not consumed by the heating-flame, so as to render the combustion perfect, and also, should the flow of the heating fluid be interrupted so as to extinguish the flame, to reig-

nite same, so that the combustion may continue upon the renewed flow of the fluid.

To this end my invention consists, broadly, in partially inclosing the burner proper with a heat-absorbing or heat-retaining device, forming an impact-shield for the gas, made of a material that will readily absorb and give off heat. This heat-retaining device has been found to enable the combustion of the gas to continue when the flame is confined in a closed compartment, for by providing the burner with this device the latter is heated to a state of incandescence, and thus tends to effect the union of oxygen with the gas more readily.

My invention also consists in the hereinabove-described combination of coöperative elements.

In the accompanying drawings I have shown my invention applied to a Bunsen burner and have also shown how the heating-burner may be used for the purpose of heating an iron; but it will of course be understood that it may be used in connection with other devices, such as blowpipes, brazing-tools, or in connection with cooking-stoves, or wherever a high degree of heat is required.

In the said drawings, Figure 1 is a sectional view of a device embodying my invention. Fig. 2 is a sectional view of a modified form of the burner-outlet. Fig. 3 is a sectional view showing my burner applied to the heating of an iron.

Like characters of reference indicate corresponding parts in the different views.

I shall describe a heating-burner embodying my invention, and afterward point out the novel features in the claims.

1 indicates a tube formed with a compartment 2, communicating with the passage 3 in the branch tube 4. The tube 1 is open at one end, as at 5, but is provided with a partition-wall 6 at the other end, forming an additional chamber 7. From this chamber 7 extends a pipe 9 up to the end 5 of the tube 1, while around the said end 5, which forms the burner, is fitted (in this instance) an ordinary elbow 8. The gas enters at G and passes up through the passage 3 into the compartment 2 and from thence to the end 5, where it is mingled with the air entering at A and issuing through

the opening adjacent to the burner of the pipe 9. Here the fluid is ignited, the flame impinging on the curved portion 8^a of the elbow 8 and issuing through the opening 8^b. 5 Within a few minutes after the lighting of the flame the elbow 8 will be heated to a red heat, and by reason of this any particles not consumed by the flame will be instantly ignited upon coming in contact with such heated 10 portion, and the combustion will, as a consequence, be perfect, leaving no smut or soot. This elbow 8, which is heated to an incandescent glow, also serves the purpose of reigniting the issuing gas in case its flow should be 15 interrupted momentarily so as to extinguish the flame, and further serves to deflect the heating-flame, so that it may be concentrated at one point.

Instead of the elbow 8 (shown in Fig. 1) 20 various other forms of heat-absorbing devices may be employed—such as, for instance, the form shown in Fig. 2, which latter shows simply a T-joint. The flame in this instance issues at both ends 11^a and 11^b of the said T- 25 joint, while the portion 11^c acts as the impact-shield. Should it be desired to have the flame issue at more than one or two points, variations may be used provided with the requisite number of openings or apertures. 30 In Fig. 3 I have shown my device applied to the heating of a flat-iron 12. This iron is hollow, but may otherwise be of any construction suitable for the purpose. The tube 1, provided with a screw-cut bushing 12^b, is inserted through a suitable opening 12^a. The 35 opening 8^b is pointed downward, so as to direct the flame on the bottom of the iron, leaving the top portion of same comparatively cool. Suitable flexible connections, such as 40 by means of rubber tubes 13^a and 13^b, are made with a gas-reservoir and a tank containing compressed air. Previous to inserting the burner into the flat-iron the former is lighted and the heat-retaining device 45 brought into a state of incandescence, when the combustion will continue after the confinement of the flame. This, of course, is but one instance of many in which this burner

could be used, but it will serve to illustrate the practical usefulness of the invention in 50 the arts where a high degree of heat is desired.

Having thus described my invention, what I claim is—

1. The combination of a comparatively- 55 closed compartment, a heating-burner located therein provided with an impact-shield so situated as not to contact with the side walls of the said compartment, and suitable connections for said burner with a gas-supply 60 and a source of compressed air, substantially as described.

2. The combination of a comparatively- 65 closed compartment, and a heating-burner located therein provided with an impact-shield so situated as not to contact with the side walls of the said compartment and in such close proximity to the burner as to constitute part of same and adapted to aid continuously in the combustion of the gases, and 70 adapted further to concentrate the issuing flame at one or more predetermined points, substantially as described.

3. The combination of a flat-iron and a 75 heating-burner located therein provided with an impact-shield so situated as not to contact with the side walls of the said iron, whereby the said shield is heated to a state of incandescence by the issuing flame, substantially as described.

4. The combination of a flat-iron and a heating-burner located therein provided with an impact-shield so situated as not to contact with the side walls of the said iron, whereby the said shield is heated to a state of incandescence by the issuing flame, and so arranged 85 as to concentrate the issuing flame on the bottom of the flat-iron, substantially as described.

Signed at New York, in the county of New 90 York and State of New York, this 19th day of February, A. D. 1900.

LEVI J. WING.
